BY *Albert J. Davis*

HIS ATTORNEY.

UNITED STATES PATENT OFFICE.

CECIL R. D'ARCY, OF WOLSTON, NEAR COVENTRY, ENGLAND, ASSIGNOR TO GENERAL ELECTRIC COMPANY, A CORPORATION OF NEW YORK.

WATTMETER.

1,003,883.

Specification of Letters Patent. Patented Sept. 19, 1911.

Application filed January 18, 1910. Serial No. 538,723.

To all whom it may concern:

Be it known that I, CECIL R. D'ARCY, a subject of the King of Great Britain, residing at Marston Mill, Wolston, near Coventry, in the county of Warwick, England, have invented certain new and useful Improvements in Wattmeters, of which the following is a specification.

My invention relates to alternating current induction watt meters and has for its object to provide a watt meter of a simple and compact construction which shall have its operating parts readily accessible.

I accomplish the objects of my invention by the use of a special form of magnetic core wherein the fluxes, due to the potential and the series windings, flow at right angles to each other, that is, the planes of the magnetic circuits for these windings are at right angles to each other, and by using that portion of the core energized by the series winding for also carrying the potential flux, and by a special arrangement of the meter parts.

The further novelties of my invention are described with more particularity in the claim annexed to and made a part of this specification.

For a better understanding of my invention, reference may be had to the accompanying drawings where—

Figure 1 shows a vertical view partly in section of a meter built in accordance with my invention, the front part of the casing being removed; Fig. 2 shows a front view of the essential elements of the meter; and Fig. 3 shows a modification of the magnetic circuit.

Referring first to Figs. 1 and 2, 1 is a casing of the meter which may be made of magnetic material. The casing is provided with holes 2, only one of which is shown, for the screws by which it is supported. Formed integral with the casing are bosses 3 and the projection 4 which is made of magnetic material. The potential core 5 is formed of suitable laminations in the usual manner, secured together by plate 6 and screws 7 at the upper portion thereof and by brackets 8 and screws 9 at the lower portion. Brackets 8 are secured to bosses 3 by screws 10. Potential coil 11 surrounds one leg of the substantially U-shaped core so as to form potential pole 11'. In operative relation with this pole is an armature 12 which may be of the usual disk type carried by

shaft 13 which is provided with a worm 14 which drives suitable registering mechanism contained in the frame-work 15. This mechanism and the bearings for the meter shaft may be constructed in any of the well known manners. In operative relation with armature 12 is a damping magnet 16, which may be constructed in the usual manner. The damping magnet, armature and shaft and registering mechanism are supported by the bracket 17 which is fastened to casing 1 by screws 18 which are tapped into suitable projections provided for the purpose in the meter casing.

Below the armature in operative relation therewith and facing the potential pole is a series core 19 which consists of two poles 19' which are energized by the series coils 20, these coils being wound so as to make the poles of opposite polarity. The inner corners of these poles are chamfered and the series coils are so arranged that their ends nearest the armature are quite flush with pole faces in order to reduce the leakage of the current flux beneath the disk. The laminations composing the series core are fastened to bracket 4 by means of screws 4', which screws may pass through slots in the core, not shown, to allow adjustment of the core to and from the armature disk.

The potential pole is surrounded by lagging coil 21 which is preferably stamped on a sheet of low resistance material and is provided with a flange 22 and lugs 23. This flange is slotted with two slots 24 to allow clamping screws 25 to pass through. These screws are tapped into lugs 23 and engage with the potential pole and are used for adjusting the position of coil 21 in the well known manner.

In addition to the magnetic circuit for the potential coil passing through the armature, there is provided by means of magnetic member 27 a shunt path for the potential flux around the armature, with an air gap 28 in the said path. This is for adjusting the phase of the potential flux in the well known manner. In order to obtain a correct phase adjustment when the

meter is used with different frequencies, a copper plate or sliding piece 29 is arranged to slide in gap 28 of the shunt magnetic circuit. This plate has at one side an arm, 5 in which are screwed the ends of screws 31. In operative relation with this arm and the screws is a fixed member 29' (see Fig. 2), having a slot 30, through which the screws pass and along which they slide. When 10 screws 31 are not screwed tight, the plate may be readily moved until the correct adjustment for the frequency desired is obtained, whereupon screws 31 may be tightened, thus holding the plate rigidly fixed 15 against member 29' in the usual manner.

It will be obvious that the path of the magnetic circuit for the potential field is through the magnetic member 5, part of casing 1, magnetic bracket 4 and through 20 core 19, and also is through the shunt path 27. The path of the magnetic circuit for the series coils is through the series coil 19 at right angles to the path of the magnetic circuit for the potential field. It will be 25 also obvious that the potential and series coils, the lagging coil 21 and the frequency correcting plate 29 are readily accessible by removing bracket 17 which is held by screws 18.

30 I find by this arrangement of the magnetic circuit and of the supporting means for the armature registering and damping magnets, I am able to construct a meter which is at the same time accurate and substantial, in a very simple manner.

While I have shown magnetic bracket 4 as formed integral with the casing such

may be formed as a separate member and bolted to the casing, as brackets 8 are bolted to the casing, and I have not illustrated 40 this construction. Further, as shown in Fig. 3, I may modify the construction shown in Fig. 1 somewhat, by not using a portion of the meter casing as part of the magnetic circuit but by continuing punchings 5 with extensions 5' in the manner 45 shown in Fig. 3. With this construction I may, if I so desire, construct a meter with the same general arrangement of magnetic circuit but without employing the casing 50 as part of the same and therefore I may use a casing of non-magnetic material.

What I claim as new and desire to secure by Letters Patent of the United States, 55

is, In an electric meter, a casing, potential and series windings, a magnetic circuit therefor comprising potential and series magnetic cores, the paths of the potential and series magnetic circuits being at right 60 angles to each other, an armature in operative relation with the potential and series windings, damping means and a registering mechanism in operative relation with the armature, and a bracket supporting the 65 damping means and the registering mechanism removably attached to the casing.

In witness whereof, I have hereunto set my hand this thirtieth day of December, 1909.

CECIL R. D'ARCY.
